UNITED STATES PATENT OFFICE.

TAYLOR K. SURFACE, OF MERNA, NEBRASKA.

FLAG-HOLDER FOR AUTOMOBILES.

1,203,937.

Specification of Letters Patent.

Patented Nov. 7, 1916.

Application filed May 3, 1916. Serial No. 95,127.

To all whom it may concern:

Be it known that I, TAYLOR K. SURFACE, a citizen of the United States, residing at Merna, in the county of Custer, State of Nebraska, have invented a new and useful Flag-Holder for Automobiles; and I do hereby declare the following to be a full, clear, and exact description of the invention, such as will enable others skilled in the art to which it appertains to make and use the same.

This invention relates to the art of supports, and more especially to an improved flag holder for automobiles and the like, and an object of the invention is to provide a device of this kind, in which improved features of construction are involved.

Another object of the invention is the provision of a flag holder having a plurality of flag staff sockets, which are pivoted to a plate so as to be adjusted in different pivoted positions whereby the flag staffs may be held in different positions.

One of the features of the invention is the provision of spring means, carried by the same pivots, that pivotally support the sockets upon the plate.

In practical fields the details of construction may necessitate alterations falling within the scope of what is claimed.

The invention comprises further features and combination of parts, to be hereinafter set forth, shown in the drawings and claimed.

In the drawings:—Figure 1 is a view in elevation of portions of the stays of the top of an automobile, showing the improved flag support as applied thereto. Fig. 2 is an enlarged detail perspective view of the flag holder detached from the stays. Fig. 3 is a view in elevation of the flag holder. Fig. 4 is a sectional view on line 4—4 of Fig. 3. Fig. 5 is a detail section view on line 5—5 of Fig. 3.

Referring more especially to the drawings, 1 designates one of the stays of the top of an automobile, and 2 denotes a plate, the lower portion of which terminates in laterally extending curved portions 3 having ears 4, each of which is provided with an aperture 5. The aperture of one ear is threaded, and extending through the aperture of the other ear is a bolt 6 which threads into the threaded aperture of the opposite ear, thereby clamping the curved portions of the plate to the stay 1. The up-

per portion of the plate 2 is sector shaped and pivoted by means of the rivets 7 to the plate is a plurality of tubular sockets 8, 9 and 10. Each of the tubular sockets has its opposite end open, and the upper end of each socket is beveled off, as shown at 11. Also secured by the rivets 7 and extending into the sockets are leaf springs 12 which act to hold flag staffs 13 in different adjusted positions. The lower portion of each leaf spring terminates in a slight lateral shoulder 14, to be engaged by the lower end of the flag staff, thereby preventing the staff from being pushed entirely through the socket. However, by exerting sufficient force on the staff, its lower extremity can be forced past the lateral shoulder 14 of the leaf spring, so that the staff may be adjusted longitudinally through the socket. It is to be noted that the socket may be adjusted angularly in different positions. In other words, the sockets may be disposed vertically, or the center socket arranged vertically and the other two sockets at angles thereto, as shown in Figs. 1 and 2, or all of the sockets may be disposed in inclined positions rearwardly and upwardly, or in inclined positions upwardly and forwardly, or in other adjusted positions.

The invention having been set forth, what is claimed as new and useful is:—

1. A flag staff holder comprising a body plate having attaching means for securing the same to a support, a plurality of staff sockets pivoted to said plate, whereby said sockets may be adjusted in different angular positions, each of said sockets having yieldable clamping means to frictionally engage the staff to hold the same in different adjusted positions longitudinally through the socket.

2. A flag staff holder comprising a body plate, a plurality of tubular sockets, means for pivoting said sockets to the plate, whereby the sockets may be adjusted in different positions, each of said sockets having its upper open end beveled off, to permit the staff to be inserted, a leaf spring secured by said pivoting means and extending into the socket and designed to frictionally engage a staff to support the same in adjusted positions longitudinally through the socket.

3. A flag staff holder comprising a body plate, a plurality of tubular sockets, means for pivoting said sockets to the plate, whereby the sockets may be adjusted in different

positions, each of said sockets having its upper open end beveled off, to permit the staff to be inserted; a leaf spring secured by said pivoting means and extending into the 5 socket and designed to frictionally engage a staff to support the same in adjusted positions longitudinally through the socket, the lower end of each leaf spring being provided with a shoulder to be engaged by the

lower extremity of the staff to support the 10 same.

In testimony whereof I have signed my name to this specification in the presence of two subscribing witnesses.

TAYLOR K. SURFACE.
